CLAIM

We claim the ornamental design for a housing for a roll towel dispenser, as shown and described.

DESCRIPTION

This application is related to U.S. Des. patent application Ser. No. 29/647,878, filed on May 16, 2018, entitled "Roller and Tab for a Roller for a Roll Towel Dispenser," which is incorporated herein by reference in its entirety.

FIG. 1 is a bottom, left, perspective view of the claimed design;

FIG. 2 is a front side view of the claimed design of FIG. 1; FIG. 3 is a rear side view of the claimed design of FIG. 1; FIG. 4 is a left side view of the claimed design of FIG. 1; FIG. 5 is a right side view of the claimed design of FIG. 1; FIG. 6 is a top view of the claimed design of FIG. 1; and, FIG. 7 is a bottom view of the claimed design of FIG. 1. The ornamental design which is claimed is shown in solid lines in the drawings. The broken lines show portions of the design that form no part of the claimed design.

1 Claim, 7 Drawing Sheets
